Josue B. Woodruff Design for Glass Case

Patented July 25, 1863

Fig. 1.

Josue B. Woodruff
Inventor

Dec. 1547

Isaac B. Woodruff, of Winchester, Conn.
Letters Patent No. 1547, dated Feb. 25, 1862.

The schedule referred to in these Letters Patent and making part of the same.

To all whom it may concern:

Be it known that I, Isaac B. Woodruff, of Winchester, in the County of Litchfield, and State of Connecticut, have invented a new and ornamental Design for a Clock Case, and I do hereby declare that the following is a full, clear and exact description of the same, reference being had to the accompanying drawing forming part of this specification, in which -

Figure 1, represents a front elevation of my new design for a clock case.

Figure 2, is a transverse vertical section of the same, the line a. a. Figure 1, indicating the plane of section.

Similar letters of reference indicate corresponding parts in the two figures.

This invention consists in the peculiar formation of the base of the case, which joins the body simply by an inverted ovoli without any intervening member, whereby a peculiar graceful boldness is imparted to the appearance of the case and at the same time the veneers, with which the case is or may be covered, need not be broken from the bottom to the top of the base, giving to the same a solid and uniform appearance; and the invention consists further in the combination with a case made or covered with veneers of rosewood or other dark colored wood of an entire gilt frame inserted in place of and used as the door and locked by a spring knob whereby the appearance of the clock case front is rendered particularly lively and pleasing to the eye.

By referring to the drawing it will be observed that the base A, joins the body B, of the case C, by means of the inverted ovoli or quadrant a, without any intervening member, and said base can therefore be covered with a continuous veneer B, from top to

2

bottom as clearly shown in Figure 2.

My case looks bold, solid and uniform whereas cases of the ordinary make show at once by their broken surface that no solid wood has been used in their construction.

The door of my case consists of an entire gilt frame D, which is secured to the case by hinges E, and locked by a spring knot C. I am aware that portions of the door frames of clock cases have previously been gilded, but the use of an entire gilt frame is entirely new to me and by its use I am enabled to impart to my cases a peculiar lively and pleasing appearance particularly if the bodies of said cases are made of or covered with some dark wood, such as black walnut, rosewood etc.

The spring knot C. is not only a simple contrivance for locking the door of the case but it also corresponds in its exterior form and color to the frame D. so that by its application the good appearance of my case is not injured.

Having thus fully described my design, what I claim as new and desire to secure by Letters Patent, is.

The design for a clock case C. the base A. of which joins the body B. by an inverted arch or quadrant A. as and for the purpose described.

And I further claim the use of an entire gilt frame D. in combination with a dark colored case C. and locked by a spring knot C. as and for the purpose specified.

Witnesses.
